UNITED STATES PATENT OFFICE.

MATTHEW G. YOUNG, OF GENEVA, OHIO.

RECHARGEABLE DRY CELL.

1,272,167.

Specification of Letters Patent.

Patented July 9, 1918.

Application filed September 11, 1917. Serial No. 190,755.

To all whom it may concern:

Be it known that I, MATTHEW G. YOUNG, a citizen of the United States, and a resident of Geneva, in the county of Ashtabula and State of Ohio, have invented a new and Improved Rechargeable Dry Cell, of which the following is a full, clear, and exact description.

This invention relates to dry cells and has for its general objects to provide an improved cell construction whereby the cell when exhausted can be readily refilled at very little expense.

A more specific object of the invention is the provision of a cell in which the shell or casing can be easily and quickly taken apart or put together so that after the cell is exhausted the zinc shell or casing can be removed and cleaned and again put together so as to be refilled.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views,

Figure 1 is a central vertical section of the cell with an intermediate portion broken away, the section being taken on the line 35 1—1, Fig. 2;

Fig. 2 is a horizontal section on the line 2—2, Fig. 1; and

Fig. 3 is a detail view showing the manner of holding the seams together and sealing the same.

Referring to the drawing, 1 designates the zinc body of the casing or shell and 2 the zinc bottom cap therefor. The body is made of a strip rolled into cylindrical form 45 with the edge 3 entered in a pocket 4 formed by the edge 5 and a strip of metal 6 soldered to the body piece. At a plurality of points drops of solder 7 serve to hold the edges of the seam together, and to prevent leakage 50 sealing wax 8 is filled into the seam. The bottom cap 2 is held by solder 9 at a plurality of points and the joint or seam between the cap and the body is closed by sealing wax 10. The whole casing or shell 55 is covered by a paper wrapper (not shown) in the usual manner.

Within the shell or casing is a lining 11 of absorbent paper which is saturated in a battery fluid composed of one pound of sal-ammoniac and one pound of chlorid of zinc crystals dissolved in distilled water in such quantity as to produce a solution of 32° Baumé. In the bottom of the casing may be placed a wooden block 12 coated with paraffin. The carbon core 13 is placed 60 in the center of the shell and the active material 14 is filled around the carbon or element 13. The active material is a carbon manganese mixture consisting of powdered peroxid or manganese and carbon of equal 70 parts. This powder is moistened with the battery fluid above mentioned and is tamped hard in the casing and around the carbon, whereby the lining 11 is pressed tightly against the sides and bottom of the 75 shell or casing.

After the cell is exhausted the sealing wax 8 and 10 is removed, as are also the drops of solder. The zinc can then be removed without disturbing the central elements and then cleaned or reversed. The absorbent paper 11 is moistened with the battery fluid and after a coating of paste is applied to the moistened paper the zinc is put back, it being preferable to tie a string 80 around the body 1 of the casing to conveniently hold the seam while the solder and wax are being applied. The bottom cap is then applied and secured in place by the solder and wax. The wax is preferably 85 made of one part resin, one part tar and one part soapstone, and the paste which is applied to the paper before the zinc shell is replaced is composed of five parts plaster of Paris, and one part wheat flour moistened 90 with enough of the battery solution to make a thin paste.

It is to be understood that the zinc is of such quality and weight that the chemical elements of the cell will be exhausted first 100 and leave sufficient strength in the zinc for the second charge of chemicals.

From the foregoing description taken in connection with the accompanying drawing, the advantages of the construction and 105 method of operation will be readily understood by those skilled in the art to which the invention appertains, and while I have described the principle of operation, together with the article which I now consider to be the best embodiment thereof, I 110 desire to have it understood that the article

shown is merely illustrative and that such changes may be made when desired as fall within the scope of the appended claims.

Having thus described my invention, I claim as new and desire to secure by Letters Patent:

1. A dry cell including a charge of chemicals, and elements acted on thereby, one element comprising a shell thicker than the shell of an ordinary cell for permitting the shell to be turned inside out when said charge is consumed, whereby the original outer face can be exposed to the action of a new charge of chemicals, said shell being made from a sheet of metal having its edges

detachably interlocked, and a detachable cap fitted over the bottom of the shell.

2. A dry cell including a charge of chemicals and a shell adapted to be turned inside out when the said charge is consumed, said shell being made of a sheet of zinc, one end of the sheet being formed with a groove throughout its length to receive the other end when the shell is initially formed and also when the shell is turned inside out, 25 means for breakably sealing the joint between the ends of the sheet, and a detachable metal cap fitted over the bottom of the shell.

MATTHEW G. YOUNG.
